UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

DOOR-KNOB.

937,472.

Specification of Letters Patent.

Patented Oct. 19, 1909.

Application filed March 11, 1904. Serial No. 197,696.

To all whom it may concern:

Be it known that I, JOHN H. SHAW, of the city and county of New Haven, in the State of Connecticut, have invented new and 5 useful Improvements in Door-Knobs, of which the following is a full, clear, and exact description, when taken in connection with the accompanying drawings, which form a part thereof, and in which—

10 Figure 1 represents a side elevation of a knob attachment embodying my invention, Fig. 2, a similar view with the escutcheon plate moved away from the door, Fig. 3, a vertical central section through the same 15 in the positions shown in Fig. 1, Fig. 4, a transverse vertical section on line 4—4 of Fig. 2, Figs. 5 and 6, front and side elevations, respectively of one of the supporting plates, in detail, Fig. 7, a detail front view 20 of the supporting plates shown interlocked, and Fig. 8, a detail front view of the clutch.

In all figures, similar letters of reference represent like parts.

This invention relates to door knobs, and 25 has for its object the provision in a door knob of a divided interlocking supporting plate or plates for securing in place a clutch which locks the knob from unscrewing on the spindle.

30 The invention consists of the production of a novel and efficient door knob, having the above referred to features and the several improvements and combinations of parts set forth and claimed hereinafter.

35 Referring to the drawings for a more particular description, the parts designated by the letter A represent a door and B the knob, with its shank or neck C.

D is the spindle, square in cross section, 40 with its corners threaded in well known manner (Fig. 4). The interior of the shank C is internally threaded to engage with the threading on the spindle (Fig. 3).

E is a clutch consisting, as shown, of a 45 substantially flat circular body, having a square axial perforation e, and lateral flanges or lugs F, to take into corresponding grooves or depressions N in the end of the shank C of the knob B. The clutch E is 50 adapted to slide upon the spindle D, but as it is incapable of rotation thereon, when it is engaged with the knob shank, it also prevents the knob and shank from rotation independently of the spindle.

55 G designates two supporting plates having

substantially semi-circular collars or flanges H, adapted to fit about the spindle D between the door A and clutch E, and when in that position prevent the movement of the clutch E longitudinally on the spindle out of 60 engagement with the knob shank. Each of these clutch supporting plates G has portions I, projecting on two sides beyond the center of the circle of which the flange H forms an arc, so that pressure on these ends will not 65 tend to tilt or dislocate the clutch. Both supporting plates have recesses P which are adapted when the two plates are in position to receive the projecting portions of the other plates, so that the two plates interlock 70 to form a continuous base or support by means of the flanges H (which thus together extend around the spindle) against the clutch, as shown more particularly in Fig. 7.

The supporting plates G may be provided 75 with elongations K which prolong the plates to a length greater than one-half the transverse axis of the escutcheon, so that when an elongated or oblong escutcheon or rose is used, as shown at M in the drawings, the es- 80 cutcheon M may be turned horizontally, as suggested in the lighter dotted lines (Fig. 4) in which position the elongated ends K of the supporting plates will project beyond the sides of the escutcheon and the plates may be 85 secured by screws or other means, in the perforations L, to the door. When the escutcheon M is turned back to its normal vertical position, as shown in heavier dotted lines in Fig. 4, it will cover the supporting plates 90 thus secured in place.

As shown more particularly in Figs. 2, 5 and 6, the ends of each of the flanges H of the supporting plates are beveled, so that they may be used as a wedge to force the 95 clutch E home into engagement with the door shank, when the supporting plate is slid into position.

Having now described my invention, (which may vary in its details without departing from the spirit thereof) what I claim and desire to secure by Letters Patent is:—

1. In a knob attachment, the combination with a screw threaded spindle; of a knob 105 adapted to be screwed thereon; a clutch capable of longitudinal movement on said spindle and only rotatable therewith adapted to engage said knob; and a support around said spindle for said clutch to hold it in en- 110

- gagement with said knob, said support consisting of two or more plates adapted to be assembled by movement toward each other edgewise, the plates when assembled forming together a support of the thickness of each plate, and the line of division between said plates being irregular with lateral recesses in one plate and corresponding projections in the other, substantially as described.
- 10 2. In a knob attachment, the combination with a screw threaded spindle; of a knob adapted to be screwed thereon; a clutch slideable on said spindle and rotatable therewith

adapted to engage said knob; a continuous support around said spindle between the door and clutch formed of a plurality of plates; and a collar, a portion of which is carried by each of said plates, substantially as described.

In witness whereof I have hereunto set my hand on the 19th day of February, 1904.

JOHN H. SHAW.
